UNITED STATES PATENT OFFICE.

THOMAS J. McCARTHY, OF LOS ANGELES, CALIFORNIA.

VACUUM TANK.

Application filed August 11, 1924. Serial No. 731,445.

To all whom it may concern:

Be it known that I, THOMAS J. McCARTHY, a citizen of the United States, residing at Los Angeles, in the county of Los Angeles and State of California, have invented new and useful Improvements in Vacuum Tanks, of which the following is a specification.

This invention relates to vacuum tanks and consists of the novel features herein shown, described and claimed.

The leading object is to make a vacuum tank in which the valves snap open and snap shut so as to make positive action.

Another object is to improve and simplify the details of construction of a vacuum tank for use in supplying fuel to the engines of motor vehicles and the like.

Other objects and advantages will appear from the drawings and specification.

The drawings illustrate the construction and operation of a vacuum tank embodying the principles of my invention.

Figure 1 is a top plan view as indicated by the arrow 1 in Fig. 2.

Fig. 2 is a sectional elevation on the line 2—2 of Fig. 1 and looking in the direction indicated by the arrows, the parts being shown in position with the float elevated and with the vent open, as when there is plenty of gasoline in the tank.

Fig. 3 is a view analogous to Fig. 2 with the float down and vent closed and the other valves open as when drawing gasoline from the supply tank by the suction of the engine.

Fig. 4 is a top plan view analogous to Fig. 1 with the cap removed to show the mechanism.

Fig. 5 is an enlarged detail of one of the valve operating levers.

Fig. 6 is a sectional detail on the line 6—6 of Fig. 5.

The details of construction and operation shown in the drawings are as follows:

The tank body 1 is a straight cylinder closed at its lower end by a cap 2 and at its upper end by a cap 3. A nipple 4 extends downwardly from the center of the cap 2 and the feed pipe 5 leading to the carburetor is connected to the nipple 4 by a union nut 6.

An inlet fitting 7 has a nipple 8 and is mounted inside of the cylinder 1 near the top with the nipple 8 extending outwardly through the wall of the cylinder. The supply pipe 9 leading from the supply tank is

connected to the nipple 8 by a union nut 10. A port 11 leads from the pipe 9 through the nipple 8 to a vertical port 12. The port 12 leads from the upper end of the fitting 7 downwardly past the port 11 and forms a settling basin 13 having a cleanout plug 14 at its lower end. The upper end of the port 12 is finished to form a valve seat 15.

The suction valve fitting 16 has a main body fitting inside of the shell 1 and a nipple 17 extending through the shell. A suction pipe 18 is connected to the nipple 17 by a union nut 19 and the suction pipe is to be connected to the engine in the usual way. A valve seat 20 is formed at the top of the fitting 16 inside of the tank and a port 21 leads downwardly and outwardly to communicate with the pipe 18. A valve seat 22 is formed from the lower end of the fitting 16 and a port 23 extends upwardly and outwardly, and an elbow shaped tube 24 is fixed in the upper outer end of the port 23 to form a vent.

Bearing arms 25 and 26 extend upwardly and downwardly from the fitting 7. Levers 27 and 28 are pivotally connected to the ends of the arms 25 and 26 and are pivotally connected to the float stem 29. A bracket 30 extends inwardly from the fitting 16 and the stem 29 slides freely through the bracket 30 at the axial center of the tank 1. Bearings 31 and 32 extend inwardly from the fitting 16 and levers 33 and 34 are pivotally connected to the bearings 31 and 32 and to the stem 29. An inlet valve 35 is connected to the outer end of the lever 27 to engage the valve seat 15. A suction valve 36 is connected to the outer end of the lever 33 and engages a valve seat 21. A vent valve 37 is connected to the outer end of the lever 34 and engages the valve seat 22. The parts are adjusted and arranged so that when the valves 35 and 36 are closed the valve 37 is opened and vice versa. The levers 27, 33 and 34 are constructed as shown in Figs. 5 and 6.

A flat end 38 has a pivot hole 39 for connection to a support and a pivot hole 40 for connection to a valve. A flange 41 is formed at the opposite end of the flat end 38 from the pivot hole 40 and forms a spring seat. A socket 42 extends from the head 41, a coil spring 43 fits upon the socket 42 against the head 41, a second flat end 44 has a pivot hole 45 for connection to the stem 29, a head 110

46 is formed integral with the end 44, and a shank 47 slides into the socket 42 with the spring 43 against the head 46, said head 46 serving as a spring seat, the object being to make an expansion lever. The lever 28 is the same as the other levers with the exception that it does not connect to a valve and simply serves as an equalizer to keep the stem 29 straight. The parts are set so that 10 when the stem 29 goes up carrying the levers past a horizontal dead center the tension of the springs 43 will snap the stem 29 upwardly and snap the valves 35 and 36 closed and snap the valve 37 open, and likewise when the stem 29 goes down past the dead center the tension of the springs will snap the vent valve 37 closed and the valves 35 and 36 open.

The float 48 fits loosely in the tank 1 and 20 has a central bearing 49. The stem 29 extends loosely through the bearing 49. A pin 50 is fixed through the stem above the float and a pin 51 is fixed through the stem below the float, there being considerable lost motion between the float and the pins. When 25 the float 48 goes up against the pin 50, continued rise in the gasoline level in the tank 1 will raise the float to raise the stem 29 until the valves 35 and 36 snap shut and the valve 37 snaps open. Then the tank will 30 continue to supply fuel to the carburetor until the gasoline goes down carrying the float 48 downwardly until the float engages the pin 51, and continued downward movement 35 of the float will move the stem 29 downwardly until the valves 35 and 36 snap open and the valve 37 snaps shut. Then continued action of the engine will cause a suction 40 through the pipe 18 to draw gasoline through the pipe 9.

A removable plug 52 is mounted in the cap 3 to be mounted in the cap 3 to be removed in priming the tank to start the engine.

45 Thus I have produced a vacuum tank in which all the valves are mounted upon expansion levers in parallel planes, the levers being connected to a float controlled stem so that when the float goes up or down the 50 valves will snap open or closed.

The bracket 30 has two arms 30^a and 30^b spaced a reasonable distance apart. An ex-

pansive spring 30^c is mounted upon the arm 30^b around the stem 29 and a pin 30^d is inserted through the stem 29 above the 55 spring so that the tension of the spring 30^c will be exerted to raise the stem 29 and assist in the snap action in closing the valves 35 and 36 at the proper time.

Various changes may be made without departing from the spirit of the invention.

I claim:

1. A vacuum tank having inlet valve mechanism, suction valve mechanism and feed valve mechanism, each of the valves 65 being mounted upon expansion levers in parallel planes, a stem to which the levers are connected, and a float having unrestricted lost motion connection with the stem, the expansion levers each comprising two ends, 70 telescopic means for connecting the ends, and an expansion spring tending to force the ends apart, so that when the float operates the stem to move the levers either way past the dead center the valves will snap 75 closed or open.

2. In a vacuum tank, a tank construction, inlet valve mechanism mounted in the tank at one side, a suction valve mechanism mounted in the tank diametrically opposite 80 the inlet valve mechanism, a vent valve mechanism mounted in line with the suction valve mechanism, a stem mounted at the axial center of the tank, expansion levers connected to the stem and carrying valves 85 for the three valve mechanisms, and a fourth expansion lever co-operating with the inlet valve expansion lever to balance the pressure upon the stem.

3. In a vacuum tank, a suction valve mechanism having a valve seat at its top, a vent valve mechanism in line with the suction valve mechanism and having its seat at the bottom, expansion levers pivotally mounted and carrying valves for the valve seat, and a stem connecting the expansion lever so that when the stem goes up the suction valve is closed and the vent valve open and when the stem goes down the suction valve is open and the vent valve closed.

In testimony whereof I have signed my name to this specification.

THOMAS J. McCARTHY.
